ACCORDION FOLDING DOOR

Guy E. Dixon, Jr., Miami Shores, Fla.

Application July 12, 1950, Serial No. 173,323

1 Claim. (Cl. 160—206)

1

This invention relates generally to doors and more particularly to a door comprised of vertical panels foldable in accordion fashion, together with mounting means therefor.

A primary object of this invention is to provide a folding door which will not sag and which will maintain an attractive appearance, when fully extended, partially extended or completely collapsed, the invention including special means to maintain the panels in two vertical positions at all times.

Another object of this invention is to provide a folding door which is easily opened and closed, and in which the spacing of the panels and the edge portions thereof is regular, so that the door has a more attractive appearance when partially closed.

Still another object of this invention is to provide a folding door in which the panels may be uniform and many of the other parts of the door and the mounting means therefor are also uniform and interchangeable, thus decreasing not only the original task of the installation but also facilitating repair whenever necessary.

A last object to be mentioned specifically is to provide a device of this character which is relatively inexpensive and practicable to manufacture, which is simple and safe as well as convenient to operate and which will give generally efficient and durable service.

With these objects definitely in view, this invention resides in certain novel features of construction, combination and arrangement of elements and portions as will be hereinafter described in detail in the specification, particularly pointed out in the appended claim, and illustrated in the accompanying drawings which form a material part of this application, and in which:

Figure 1 is a side elevational view of a complete door assembly;

Figure 2 is a horizontal sectional view taken on the line 2—2 in Figure 1;

Figure 3 is a view of the structure, viewed as from the same line as 2—2, but showing the door in completely collapsed or open position;

Figure 4 is a fragmentary vertical sectional view, on an enlarged scale, taken on the line 4—4 in Figure 3;

Figure 5 is an enlarged fragmentary detail view, horizontal vertical section in character, taken on the line 5—5 in Figure 4;

Figure 6 is a vertical sectional view taken on the line 6—6 in Figure 1;

Figure 7 is a similar horizontal sectional view taken on the line 7—7 in Figure 1; and

2

Figure 8 is a grouped view of pivot pin structure which is used in several places in the assembly.

Similar characters of reference designate similar or identical elements and portions throughout the specification and throughout the different views in the drawings.

Referring now to the drawings in detail, this invention is adapted to be used with an environment including a doorway or the like in which the vertical stiles of the doorway are indicated at 10. Overhead structure of the doorway will ordinarily include a header or beam 12 and may also include an overhead plate 14, ordinarily of wood, another layer 16 of wood or plaster, a plaster stop 18 provided in duplicate, it being understood that the specific construction of the doorway or archway is relatively immaterial in this application for patent.

A track 20 will in all cases be provided and this track 20 is illustrated as disposed between the plaster stops 18, the track having depending lateral wall portions 22 terminating in outwardly extending flanges 24 which are secured to the plaster stops and to the beam 12, or analogous structure, by means of the screws 26. The track is at least substantially co-extensive with the width of the door opening. The track has a pair of opposed inwardly extending flanges 28, the inner terminals thereof being turned upwardly and the upper surfaces thereof being longitudinally grooved to comprise a pair of trackways 30.

A plurality of vertical inflexible panels 32, preferably constructed of wood or the like and of equal length, comprise the main portions of the door. Each panel 32 is provided, on each vertical edge portion thereof with a slot 34 extending the full or substantially the full length of each panel and being somewhat key-hole shaped in cross-section, the inner end of the slot being enlarged as will be clearly understood from an inspection of Figure 6. The panels 32 are connected together hingedly by a plurality of strips 36 of flexible material such as woven fabric or plastic, the vertical edge portions of each strip being enlarged as indicated at 38 to fit snugly within the enlarged inner end portions of the slots 34. The end portions of the strips 36 are coated with a substance such as flexible glue which makes the end portions of the strips which are exposed more resistant to wear and unravelling when fabric is used, while the portions within the slots are adhesively secured therein. The addition of the said substance to the ends of the strips is diagrammatically indicated at 39 in Figure 1.

The strip 36 at one side of the door assembly is, as best indicated in Figure 7, secured to the stile 10 by means of a simple elongated bracket 40 having a substantially semi-circular flange 44 extending along one edge of the bracket to receive the bead 38 or enlargement on the corresponding ends of the strip 36, this bracket 40 being secured by screws 42. At the opposite side of the door assembly, the outermost panel 32 is provided with an elongated bumper or stop 46, illustrated in Figures 1 and 2, this stop being ordinarily comprised of rubber or another resilient substance and having a reduced neck portion to fit within the corresponding slot 34 and an enlarged inner edge portion to fit within the enlargement in the slot 34 thus holding the stop or bumper 46 in place.

Each panel 32 is supported by means of an elongated screw 48 which is inserted into the upper edge portion of each panel and extends upwardly beyond the same for pivotal engagement with an axle member 50. This axle member extends transversely of the headed upper end portion of the screw 48 and carries a pair of rollers 52 which are freely rotatably mounted on journal portions 54 at the ends of the axle member 50, these rollers 52 being dimensioned and otherwise adapted to roll within the trackways 30 of the track 20.

An elongated plate 56 on the top of each panel 32 and a similar elongated plate 58 on the bottom of each panel 32 are secured by screws 60, and these plates 56 and 58 move at all times with the panels 32. The plates 56 and 58 are provided with terminal portions 62 offset from the longitudinal axes of the plates, in opposite directions, and these terminals 62 are apertured to receive pivot pins 64 having annular grooves 66 to receive split washers 68. A plurality of elongated bars 70 at the top of the door and 72 at the bottom of the door are pivoted at their center points to the central points of the corresponding plates 56 and 58, by means of shank portions of the screws 48, in the case of the upper plate 56 and bars 70, and by simple pivot pins 74, in the case of the lower plate 58 and bars 72. The ends of the bars 70 and 72 are offset from the longitudinal axes of the bars, in opposite directions, similarly to the offset terminals 62 of the plates 56 and 58, and the pivot pins 64 connect to the apertured ends of the bars 70 and 72 with the said terminals 62.

The screws 48 are undercut intermediate their lengths to receive washers 76 which limit the entrance of the screws into the tops of the panels 32. These washers 76 being disposed on the underside of the top plates 56, and other washers 78 are interposed between the top plates 56 and the corresponding bars 70. The screws 60 aid in supporting the panels 32, since they cooperate with the plates 56 and split washers 76, these washers 76 being sufficiently sturdy to carry considerable weight. Similar washers, also numbered 76 in the drawings, are inserted on the simple pivot pins 74 between the lower plates 58 and the corresponding bars 72.

At what may be considered the outer end of the door assembly, disposed to the left in Figures 1 and 2, a shortened bar 80 is connected to the midpoint of the corresponding plates 56 and 58. An attaching plate 82 is provided at the top and bottom of the door assembly and serves to locate and guide the corresponding ends of pairs of the plates 56 and 58 and bars 70 and 72. These attachment plates 82 being best illustrated in Figures 1, 2 and 3 as comprised of angle plates whereof the

vertical flanges 84 are secured to the corresponding stile 10 by screws 86, while the horizontal flanges are provided with opposing elongated slots 88 to receive sliding terminal elements 90 which may be, as indicated by the reference numerals, pivot pins 64, with a suitable complement of washers if necessary. The central portions of the horizontal flanges of the angle attachment plate 82 will be recessed, as indicated at 90, to receive the adjacent screws 48 and pivot pins 74 when the door is fully collapsed or opened.

The operation of this invention will be clearly understood from a consideration of the foregoing description of the mechanical details thereof, taken in connection with the drawings and with the above recited objects of this invention.

In recapitulation, it may be noted that the main weight of the door will be borne by the track 20, while the lazy-tong systems comprised of the plates 56 and 58 and bars 70 and 72 prevent misalignment of the panels 32. It will also now be clear, in the light of the foregoing description, that the folding door assembly is easily mounted in place, easily operated, attractive in appearance and generally qualified to amply achieve the above recited objects. Further description is apparently unnecessary.

Having described the invention, what is claimed as new is:

A folding door comprising a plurality of inflexible vertical panels having vertical slots in and substantially coextensive with vertical edge portions of said panels, said slots having their inner ends enlarged, strips of flexible material substantially coextensive with said slots and having their vertical edge portions enlarged and adhesively secured in the enlarged inner ends of said slots, said strips connecting the panels in series, a horizontal track above said panels, rollers supported on said track and having axle members connected to and supporting said panels, a lazy-tong system between said track and the upper ends of said panels, another similar system at the bottom of the door, each system including similar elongated plates secured to the ends of the panels, bars equal in length to said plates and pivoted at their center points to the center points of said plates, said plates and bars having pivotally connected terminals offset from the longitudinal axes of the plates and bars so that said panels can collapse into parallel relation when the door is fully opened, an attaching plate for each of said systems, said plates having slots, one of said plates and one of said bars in each of said systems having terminal elements pivotally and slidably mounted in said slots.
